UNITED STATES PATENT OFFICE.

ELIHU THOMSON, OF LYNN, MASSACHUSETTS, ASSIGNOR TO THE THOMSON-HOUSTON ELECTRIC COMPANY, OF CONNECTICUT.

CUT-OUT FOR ELECTRIC-ARC LAMPS.

SPECIFICATION forming part of Letters Patent No. 307,819, dated November 11, 1884.

Application filed April 12, 1884. (No model.)

To all whom it may concern:

Be it known that I, ELIHU THOMSON, a citizen of the United States, and a resident of Lynn, in the county of Essex and State of 5 Massachusetts, have invented certain new and useful Improvements in Cut-Outs for Electric-Arc Lamps, of which the following is a specification.

My invention relates to apparatus for automatically forming a shunt or safety branch around the electrodes of an electric-arc lamp in case of an abnormally-long arc.

My invention is designed more especially for use with electric-arc lamps arranged in series upon an electric circuit, and is intended to furnish a simple and effective device whereby the lamps may be automatically cut out independently of one another, as with those cut-out devices in which the shunt or safety branch is controlled by a magnet of high resistance in a derived circuit around the carbons.

The object of the invention is also to give independence of action to the cut-out device 25 of a number of arc lamps in the same circuit, when the cut-out switches are controlled by electro-magnets in the main or principal circuit with the carbons, as in the well-known Varley cut-out.

30 My invention consists in breaking the arc of a lamp if it reach an abnormal length by the repellent or attracting influence of a magnetic field bearing on the arc, and produced by the agency of a permanent or electro magnet, a solenoid, or other suitable device, and thus calling into action the particular cut-out apparatus of the lamp in which the abnormal arc occurs.

The cut-out apparatus may be a Varley or 40 other cut-out apparatus of suitable kind to be acted upon by the disruption of circuit at the arc.

Some of the ways in which my invention 45 may be carried into practice are shown diagrammatically in the accompanying drawings.

The parts illustrated are of any desired kind, and the manner of mounting them in the lamp is immaterial.

50 The invention consists in the manner of electrically connecting and arranging the parts with relation to one another.

Figure 1 illustrates diagrammatically a way of carrying out the invention in connection with a Varley cut-out. Fig. 2 is a modified arrangement for giving increased influence to the displacing-magnet at the time that the arc lengthens abnormally. Fig. 3 shows an improved disposition and manner of mounting the displacing-magnet. Figs. 4 and 5 illustrate other modifications of the invention. Fig. 6 illustrates a device that may be employed for keeping the controlling device of the cut-out in unchanged relation to the arc while the lamp is in operation.

In Fig. 1, B indicates an electro-magnet in 65 the main or principal circuit with the electrodes of an electric lamp whose arc is indicated at E. The magnet B acts on its armature A against the force of a retractor to keep the contacts F of a branch or safety circuit, 7, around the lamp normally open, after the manner of the main-circuit magnet in the well-known Varley cut-out.

M is a magnet suitably supported, so that 75 one of its poles will be near the arc and will exert a repellent or attracting effect thereupon, according to the pole presented. At any time during burning it will displace an abnormally-lengthened arc produced by a failure to feed, so as to effect a rupture of circuit, at which 80 time the armature A, being released, is allowed to shunt the lamp through suitable contacts at F. Should the carbons after the extinguishment again come together, the magnet B will open the contacts at F and allow the lamp 85 to resume its action.

In the modified arrangement shown in Fig. 2 the permanent magnet M is replaced by an electro-magnet, M', which is brought into action by other agencies—as, for instance, by a 90 derived-circuit electro-magnet, D—to break the arc if it become abnormally long. The shunting or switching appliances for forming the path around the lamp are here omitted for the sake of simplicity. The coils of magnet 95 M' are controlled by shunting-contacts S, which are normally closed by the action of a spring, G, acting on the armature-lever carrying one of said contacts. The armature-lever is acted upon by the magnet D of high 100 resistance in a derived circuit around the arc, while the contacts S close a shunt around the

coils of M'. When the shunt at S is opened, the coils of M' are in the lamp-circuit, as indicated, and said magnet is then energized and acts strongly upon the arc to disrupt it. The 5 electro-magnet D and refractor G are adjusted so that when the arc becomes abnormally long the magnet will have sufficient power to open the contacts S, whereupon the magnet M' immediately breaks the arc, as before explained. 10 It is not necessary that the current be permitted to flow in coils of M' only with abnormal arcs. The contacts S may open during normal arcs, or may be dispensed with, the current then flowing constantly in coils of M'. 15 The coils of M' may be, if desired, in a derived circuit of high resistance around the arc, as indicated in Fig. 5, so that its power to displace an arc will increase with the increased length of arc. The coil of M' in this case 20 may have a resistance of seven hundred ohms around an arc which abnormally lengthened may be ten ohms.

In Fig. 3, M M indicate a two-branched or horseshoe magnet whose poles N S affect the 25 arc E and displace it. The magnet M M may be a portion of the frame of the lamp, as shown, and serve in whole or part to sustain the lower holder.

In Fig. 4 the coil C, properly arranged with 30 relation to the arc, is in the main circuit and affects the arc at E to drive the latter aside until it breaks circuit. At the instant this occurs the current forces its way through the film of a film cut-out, indicated at K, and constructed as described in a prior application 35 for patent filed by me February 25, 1882, No. 53,726, thus forming the safety-circuit around the carbons.

K indicates the film of insulating material 40 which normally keeps the electrodes a b out of connection, one or both of the latter being preferably acted upon by a spring. The film is of thin tissue-paper oiled, or of other insulating material. When the difference of potential between a and b, owing to breakage of 45 the arc or other cause, becomes sufficiently high, the current breaks through the insulating-film and the connection between the electrodes a b is thus formed.

In order to keep the magnetic field constantly in the same relation to the arc in an ordinary or non-focusing electric lamp, the magnet may be supported from a mechanism that shall permit it to shift in position correspondently with the shifting of the arc by 50 consumption of the carbons. Such an arrangement is indicated in Fig. 6, and is substantially the same as the one shown in a prior application filed by me December 18, 1883, No. 114,967. 60

R indicates the carbon-carrier, gearing with a wheel, f, keyed to or upon the same shaft with the wheel g, which latter gears with a bar, d, supporting the magnet M. The wheels are so proportioned that the downward movement of the magnet shall exactly correspond with the downward shifting of the arc due to the consumption of the electrodes. 65

Other mechanical devices may obviously be used for permitting the desired movement of 70 the magnet or solenoid.

What I claim as my invention is—

1. In an electric-arc lamp, the combination, with cut-out devices for forming a branch circuit around the lamp, of a magnetic field near 75 the arc, whereby it may be displaced or ruptured, as and for the purpose described.

2. The combination, with the electrodes in an electric-arc lamp, of a bar magnet or magnets arranged parallel to said electrodes for 80 the purpose of displacing the arc.

3. The combination, with the electrodes in an electric lamp, of an arc-displacing magnet or solenoid having its coils in a derived circuit around the arc. 85

4. The combination, with a short or shunt circuit closer, of a magnet in the carbon-circuit for keeping the circuit-closer open, and means, substantially as described, whereby the arc may be displaced through the influence of a 90 magnetic field.

Signed at Lynn, in the county of Essex and State of Massachusetts, this 7th day of April, A. D. 1884.

ELIHU THOMSON.
